UNITED STATES PATENT OFFICE.

ALFRED BONOM, OF PATERSON, NEW JERSEY.

REVERSIBLE TURBINE.

1,313,058.

Specification of Letters Patent. Patented Aug. 12, 1919.

Application filed December 26, 1918. Serial No. 268,362.

To all whom it may concern:

Be it known that I, ALFRED BONOM, a citizen of France, and a resident of Paterson, in the county of Passaic and State of New Jersey, have invented a new and Improved Reversible Turbine, of which the following is a full, clear, and exact description.

This invention relates to high speed fluid turbines and has particular reference to reversible steam turbines.

Among the objects of the invention is to provide a direct action and reaction turbine comprising a plurality of oppositely moving or movable members or rotors so designed and constructed as to possess maximum efficiency with a minimum amount of weight of material and expenditure of steam or fuel.

Another object of the invention is to provide improved labyrinth packings between all relatively movable parts subjected to the steam pressure.

Another object of the invention is to provide for delicacy of adjustment of the labyrinth packings.

Another object of the invention is to provide for a perfect counterbalance of the expansive force of the driving fluid in every direction whereby the rotors are relieved from end thrust.

A still further object is to provide compound rotor members which may be described as inner and outer rotors, said rotors involving two stages, one for high pressure and the other for low pressure, and the inner rotor comprising a disk member pertaining to the high pressure stage and another disk member pertaining to the low pressure stage, each disk member being opposed by a similar disk member of the outer rotor.

Another object of the invention is to improve the specific construction of the rotors with respect to the manner of making the blade structures, and the means for supporting them upon the disk elements.

A still further object is to provide oppositely movable sets of blades each set constituting a circular series of blade elements with flexible supporting means therefor carried by one of the disks, adjacent sets of blades of one rotor being interspersed with corresponding sets of blades carried by the opposite rotor and with peculiar labyrinth packings between each set of blades and the next inner or outer set carried by the opposite disk.

Another object of the invention is to provide a compound turbine engine having high pressure and low pressure stages, and with means causing pressure fluid to pass outward radially through respective stages.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical central longitudinal section of the upper half of a steam turbine made in accordance with my invention.

Fig. 2 is an enlarged vertical longitudinal section of a portion of the high pressure stage structure.

Fig. 3 is a similar view of the low pressure stage structure.

Fig. 4 is an enlarged longitudinal section of the high pressure labyrinth bearing packing.

Fig. 5 is a similar view of the preferred form of the low pressure labyrinth bearing packing; and

Fig. 6 is a modified form of transmission gearing between the main shaft and the sleeve on which the rotors are respectively connected.

Referring now more specifically to Fig. 1 the main shaft is indicated at 10 and fixed directly thereon by any suitable means is the structure termed the inner rotor 11 and comprising a high pressure disk 12 and a low pressure disk 13. Secured also to this shaft is a beveled gear 14, and also fixed to the shaft at the end opposite from the gear 14 is a clutch member 15 of any suitable type.

The outer rotor 16 comprises three disk members 17, 18, and 19, the member 17 being opposed to the disk 12 of the high pressure stage construction, and the disk 19 being opposed to the low pressure disk 13. The disk 18 is located between the two stages and provides a means for the return of the pressure fluid to a position adjacent to the shaft whence it will act through the low pressure stage in a radially outward direction. The outer rotor comprises also two sleeve extensions 20 and 21 journaled either directly upon the main shaft 10, or upon

this shaft through suitable bearing bushings 22 and 23 respectively. Fixed in any suitable manner to the end of the sleeve 20 remote from the rotor disk is a gear 24 opposed to the gear 14 and between which are interposed a plurality of beveled idlers 25 each journaled upon a fixed support 26 by means of a multiple bushing bearing 27.

Surrounding and inclosing the rotors is a stationary casing 28 having a steam inlet 29 and an exhaust dome or drum 30. The inlet 29 has a restricted passageway 31 leading into the hollow hub 32 of the high pressure stage structure whence the steam 10 is delivered radially outward through an annular outlet 33 into driving coöperation with alternately arranged blades 34 and 35 carried respectively by the inner and outer rotors. The flow of the steam thus is radial 15 and outward from the hub 32 while the expansive force thereof is exerted against the two sets of blades 34 and 35 circumferentially causing the rotors to which these blades are connected to rotate in opposite directions, 20 either actually or relatively. From the periphery of this high pressure stage structure the steam passes through the passageway 36 between the disks 12 and 18 to the hollow hub 37 of the low pressure stage structure, 25 whence the steam again flows radially outward so as to act against the reversely arranged sets of blades 38 and 39 carried respectively by the disks 13 and 19 of said low pressure stage structure, the steam acting as before described to expand circumferentially while it flows radially outward and is delivered finally into the exhaust dome 30.

One of the serious problems to be met in 40 perfecting a steam turbine is to insure substantially free rotation of the rotors with a substantially steam tight packing system to prevent leakage of steam and consequent loss of efficiency. This problem I have 45 solved by the provision of a new and efficient system of labyrinth packings which constitutes one of the important features of this invention. Referring now therefore more specifically to Fig. 4 I show the high 50 pressure packing devices as comprising mating pairs of inner and outer rings 40 and 41 having screw threaded engagement respectively with a sleeve 42 mounted adjustably upon the hub extension 32' from the 55 disk 17 and the hub extension 28' constituting a portion of the stationary casing 28. Each ring 40 comprises a hub 40^a, a flat annulus 40^b, and a series of concentric annular flanges 40^c and 40^d. The flanges 40^c 60 are preferably exactly alike except for a slight difference in diameter. The flange 40^d is the largest and is provided with a plurality of outwardly projecting fins 40^e. Each of the flanges just described has a laterally projecting fin 40^f the free edges of

which all lie in the same plane perpendicular to the axis of the rotor to which they pertain. Again, each flange has an inwardly projecting fin 40^g. Each ring 41 comprises a hub portion 41^a, a flat annulus 41^b and a plurality of concentric annular flanges 41^c and 41^d having the same general characteristics of the corresponding flanges 40^c and 40^d of the mating ring. The flange 41^d is shown 70 provided with a pair of inwardly projecting fins 41^e, the points or edges of which have close relation to the outer surface of the hub 40^a. Again, each flange 41^c and 41^d has a laterally projecting fin 41^f all of the edges of which lie in the same plane 80 and in close proximity to the inner radial wall of the web 40^b of the mating ring, while the edges of the fins 40^f of said latter ring have similar proximity to the inner radial wall of the web 41^b. While each of the 85 flanges 40^c or 41^c has a smooth cylindrical outer surface the inwardly projecting fin of the next outer flange has close contact with said smooth surface, that is to say, the fins 40^g of the ring 40 bear respectively upon 90 or close to the smooth exterior surfaces of the flanges 41^c and 41^d of the ring 41, while the fins 41^g of the flanges 41^c bear respectively upon the outer surfaces of the flanges 40^c, and the fins 41^e have similar bearing 95 upon the outer cylindrical surface of the hub 40^a. Obviously each of these ring members is made so as to be perfectly circular and symmetrical with respect to the axis of the rotor to which it pertains, and hence 100 all of the respective flange and fin features are precisely alike and interchangeable so that when each mating pair of rings 40 and 41 are slipped together as shown and properly adjusted as to the force of the bearing 105 contact between adjacent features, this adjustment of the rings 40 with respect to the several mating rings 41 may be effected by the rotation of the sleeve 42 around the extension support 32', and the position of 110 the sleeve 42 may be locked after adjustment by means of a set screw 42'. There are provided in the form shown in Fig. 4 at least fifteen lines of contact between each two relatively movable parts making up the system. It is furthermore to be noted that the 115 line or course through which the steam would be obliged to pass to escape through this labyrinth is exceedingly circuitous, making it a practical impossibility for any leakage 120 to result even though the actual contact between adjacent and relatively movable parts is slight or entirely wanting. Furthermore this exemption from leakage 125 is multiplied as many times as there are pairs of mating rings throughout the packing. While each ring 40 may abut at its hub squarely against the next similar ring so that no steam can escape between any 130 of these rings and the sleeve 42 on which

they are fitted, so also the rings 41 have steam tight fit in the hub extension 28' and abut squarely against one another. It, of course, is understood that between each pair 5 of rings 40 and 41 there is free rotating movement, but the course of steam that would seek to escape through the packing leads through not only one set of fifteen points or contact lines in each pair of rings 10 but also through as many multiples of fifteen as there are pairs of rings. Furthermore all condensation water that may accumulate in the labyrinths will add to the difficulty for the steam to escape, but will 15 add no appreciable resistance to the rotation of the rotors. These packing rings 40 and 41 when put in place are locked by means of adjustable abutment rings 43 and 44 respectively which hold the packing 20 rings in place with any suitable degree of frictional contact with the other adjacent rings.

In Fig. 5 I show in detail the construction of labyrinth packings that may be used 25 in connection with the low pressure stage construction, such packings being indicated at 45 at three different parts in Fig. 1. This type of bushing comprises mating series of inner and outer packing rings 46 and 47 respectively coöperating with a sleeve or bearing bushing 48 through a sleeve 49, with respect to the rings 46, and with an outer member 50 which at the central portion of Fig. 1 is indicated as constituting a flanged extension 30 from the intermediate disk 18 of the outer rotor, which the member 48 is indicated as constituting a flanged extension of the disk 13 of the inner rotor. The adjustment of the sleeve 49 around and along the 35 support 48 serves to cause the longitudinal adjustment of the mating rings 46 and 47 in a manner similar to the adjustment of the rings 40 above described, and this sleeve 49 may be locked in adjusted position by means 40 of a set screw 49'.

With reference especially to the detailed construction of the rings 46 and 47 it will be noted that each ring 46 comprises a hub portion 46^a, a central outwardly projecting radial web 46^b, oppositely arranged circumferential flanges 46^c projecting laterally from opposite sides of the web 46^b, and an outside double flange 46^d. Each flange 46^d has a plurality of outwardly projecting fins 46^e and a laterally projecting fin 46^f, and also inwardly projecting fins 46^g. The flanges 46^c have laterally projecting contact edges or fins 46^f and inwardly projecting edges or fins 46^g similar to those features of the 45 flanges 46^d.

Each packing ring 47 comprises a hub portion 47^a, a central web 47^b, and laterally projecting flanges 47^c and 47^d. The flanges 47^c have a plurality of inwardly projecting fins 47^e, and each of the lateral flanges has a lat-

erally projecting fin 47^f; also the flanges 47^c have inwardly projecting fins 47^g.

While the hub portions 46^a and 47^a of these members have threaded connection respectively with the sleeve 49 and hub extension 50 the directly opposite surfaces of these parts have smooth cylindrical surfaces with which the fins 47^e and 46^e of the adjacent parts coöperate respectively. Likewise the fins 46^g and 47^g coöperate respectively with the smooth outer surfaces of the flanges 47^c and 46^c respectively. Also the laterally projecting fins or edges 46^f and 47^f coöperate respectively with the radial webs 47^b and 46^b. As in the packings for the high pressure stage structure of Fig. 4, it is obvious that the path of escape of steam of this packing of Fig. 5 is so circuitous that it is practically impossible for any loss of efficiency from this cause even though the actual contact between relatively movable parts may be barely perceptible. Examples of the high pressure packing such as shown in Fig. 4 are indicated at three places in Fig. 1 guarding all points subjected to steam at 90 high pressure, and thus I am able to construct a practical steam turbine having relatively loose bearings without any loss of efficiency.

By referring again to Fig. 1 it will be noted that the disks 12 and 17 of the high pressure stage structure are so disposed with respect to each other that there is a tendency for the expansive force of the steam to act to cause the separation of the disks in a direction parallel to the axis of the shaft 10, and obviously this force is exerted equally in two opposite directions. Likewise the expansive force of the steam in the low pressure stage structure tends to force the disks 13 and 19 in opposite directions parallel to the shaft and with equal degrees of force. In this connection it is to be noted particularly that the diameter of the disks of the respective stages is calculated according to the expansive force of the steam while passing through said stages. That is to say the diameter of either disk 12 or 17 is universally proportional to the steam pressure acting thereon. Since, therefore, the disks 12 and 13, constituting the inner rotor, are coupled together they constitute a rigid unit, and likewise the disks 17 and 19 are coupled together and constitute the outer rotor. By making the disks 13 and 19 materially larger in diameter than the disks 12 and 17 the lower pressure of the steam acting longitudinally therebetween will have the effect of counterbalancing the tendency of the high pressure steam in the high pressure stage to cause longitudinal movement of either of the disks 17 or 12.

Any suitable lateral bearings may be provided for the main shaft 10 and sleeve extensions or hubs coöperating therewith or

therearound. By reference, however, to Fig. 1 it will be noted that I provide an adjustable tapered bearing bushing 51 having a similarly shaped brass 52 coöoperating with 5 a tapered portion 10^a of the main shaft. The bushing 51 has an end extension and a terminal flange 53 through which adjustment screws 54 project into the end portion 55 of the hub extension 21 to the outer rotor. 10 Hence by the turning of these screws 54 the bearing bushings 51 and 52 may be adjusted to compensate for wear. Other compound bearing members 56 are arranged between the outer surface of the extension 21 and 15 stationary bearing box 57. Any suitable provision for lubrication may be made in connection with these bearings.

Any suitable devices may be provided to control the actual or relative rotation of the 20 two rotors for the purpose of determining the direction and rate of speed of these parts. As already referred to the clutch member 15 is fixed to the shaft, and adjacent yoke member 58 is splined to a shaft extension 10'. 25 The sleeve extension 55 includes also clutch teeth 55' between which and the teeth of the clutch member 15 a shiftable clutch collar 59 coöperates so as to couple the shaft extension 10' directly to the shaft 10 through 30 clutch members 15 and 59 or to connect the shaft extension 10' with the outer rotor through the clutch members 59 and 55'.

Referring now more specifically to Figs. 2 and 3 for a further description of the propelling blades, 60 indicates the type of flexible ring connection I prefer to use between the blades 35 and the high pressure disk 17. Each of these rings has an anchorage portion base 61 and a relatively slender neck 40 portion 62 between the same and the ring 60. The other side of the steam space and parallel to the ring 60 is a companion floating ring 63 of the same diameter as the ring 60. The blades 35 are connected up in circumferential series and are fitted in the rings 60 and 63 by any suitable interlocking means such as dove-tailed tenons and grooves, and are finally secured therein by means of fingers 64 and 65 fixed to the rings 45 50 55 60 and 63 respectively. With respect to the disk 12 I provide rings 66 each having an anchorage base 67 and a flexible neck connection 68. Opposite each of these rings 66 is a companion floating ring 69 and between the rings 66 and 69 are locked a series of 60 blades 34 by means of fingers 70 and 71 fixed to the rings 66 and 69 respectively. Each ring base 61 or 67 is provided with a plurality of laterally projecting concentric contact fins 72 which coöperate with the mating floating ring 69 or 63 of the opposite set of blades respectively. Between each pair of concentric fins 72 is a fin 73 projecting laterally outward from the mating floating 65 ring 69 or 63 respectively. Thus it will be

seen that each pair of mating base and floating rings constitute a packing labyrinth serving to prevent the escape of steam in such a direction as would interfere with the efficiency of the machine.

70

In Fig. 3 I show a detail of the blades for the low pressure stage construction. In this connection for the blades 38 I provide rings 74 having bases 75 with flexible neck connections 76. Opposite each ring 73 is a 75 companion floating ring 77 which coöperates directly with the base 78 of the ring 79 located next thereto inward. The parts 78 and 79 are connected by a flexible neck 80. Opposite each ring 79 is a floating ring 81 80 which coöperates in turn with the base 75 of the next inward series of blades. The blades 38 are held to the rings 74 and 77 by means of dovetailed interlocking connections and detachable fingers 82 and 83 respectively. Likewise the series of blades 39 are anchored to the rings 79 and 81 by interlocking connections and detachable fingers 84 and 85 respectively. The rings in this form of the invention are of a simpler 90 nature than those in Fig. 2, having a lower number of labyrinth fins 86. The flexibility of the necks 62, 68, 76, and 80 provides for the accommodation of the several series of blades to variations of expansion due to 95 changes in temperature, and also insuring the accurate centering of the several annular series of blades automatically due to the high speed of rotation.

Fig. 6 shows a slight modification in design of bevel gearing between the two rotors. In this form the shaft 10 has a bearing in the hub portion of the gear 24' and to the end of the shaft is secured a similar gear 14'. Between these two gears are arranged a circular series of idlers 25' each mounted upon a stationary stud 27' constituting a part of or an extension from the stationary bearing box 87. Each bearing or set of bearings has an oil inlet pipe 88 whereby complete circulation of oil may be observed, the discharge of the oil from the bearing being through a large duct 89 at the bottom of the bearing box. Another delivery pipe for oil is shown at 90 along the inner end of the bearing box adjacent to the sleeve extension 20' to which the gear 24' is attached. One or more rings 91 are fixed to the shaft and serve to deflect the oil whereby the creeping thereof along the shaft 115 120 beyond the bearing box is permitted.

I claim:

1. The herein described compound steam turbine comprising an inner rotor and an outer rotor, the inner rotor comprising a 125 high pressure disk and a low pressure disk, the outer rotor comprising a high pressure disk coacting with the first mentioned high pressure disk, a low pressure disk coöperating with the aforesaid low pressure disk, 130

rigid connections between the aforesaid disks of the outer rotor, and a third disk extending between the two disks of the inner rotor, means supporting the two rotors for independent rotation in relatively opposite directions, and means to cause the flow of motive fluid outward radially between the two sets of coöperating disks.

2. In a compound steam turbine, the combination of an inner rotor comprising high pressure and low pressure disks, an outer rotor comprising a high and low pressure disk coöperating respectively with the disks of the inner rotor, supporting means for the several rotors, and means to cause the steam to flow radially outward between one pair of disks and thence subsequently radially outward through the other pair of disks.

3. The herein described compound steam turbine comprising a shaft, an inner rotor fixed thereto and comprising a plurality of blade carrying disks, an outer rotor supported for rotation around said shaft in a direction opposite from the rotation of the inner rotor, the outer rotor comprising a plurality of blade carrying disks coöperating each to each with the aforesaid blade carrying disks, and means to cause the steam to pass radially outward between each pair of coöperating disks in succession.

4. The herein described compound steam turbine comprising a high pressure stage and a low pressure stage, each stage comprising a pair of coöperating blade carrying disks, and means to cause the steam to pass radially outward through the blades of the high pressure stage and thence radially outward through the blades of the low pressure stage, the two stages being coaxial but one being arranged at the side of the other.

5. In a high speed fluid turbine, the combination of two coaxial spaced disks representing independent rotors, a succession of radially spaced blades and means connecting them to each disk, the blades of one disk being arranged in alternation with those of the opposite disk, the supporting means for each series of blades comprising a pair of coaxial rings of the same diameter, one of the rings being floating, and an attachment base for the other ring of a different diameter, the

next adjacent series of blades of the other disk being approximately of the same diameter as said attachment base and lying adjacent thereto.

6. In a high speed steam turbine, the combination of a pair of coaxial spaced disks representing independent rotors, a radially disposed succession of spaced series of blades for each rotor, the series of blades for one rotor being interspersed in alternation with those of the other rotor, and means to anchor the several series of blades to their rotors, said anchorage means comprising base rings of a greater diameter than the series of blades supported thereby, but of the same diameter as the alternate blades of the other disk.

7. In a high speed steam turbine, the combination of a main shaft, a sleeve journaled for rotation therearound, a pair of rotors connected respectively to the shaft and the sleeve, an adjustable tapered bearing surrounding the shaft and connected to the sleeve to take up for wear, and means coöperating with the shaft and the sleeve to control the actual rotation of the shaft and sleeve.

8. In a compound steam turbine, a pair of rotors adapted to operate in relatively opposite directions, each rotor comprising a high pressure disk and a low pressure disk coöperating respectively with similar disks of the other rotor, and means to support said disks so that the pressure between the high pressure disks will be exerted equally in opposite directions, while the pressure between the lower pressure disks will likewise be exerted in opposite directions.

9. In a compound steam turbine, the combination of a pair of rotors, each comprising a high pressure disk and a low pressure disk and means rigidly connecting said two disks, and means supporting the rotors for movement in relatively opposite directions, the steam at whatever pressure acting against any disk to be reacted by the steam pressure in the opposite direction against the other disk of the same rotor whereby a perfect counterbalancing effect is produced irrespective of the variations in steam pressure while passing through the turbine.

ALFRED BONOM.
